Des. 214,644
Patented July 8, 1969

214,644

COMBINATION TWIN REFUSE RECEPTACLE UNIT AND UTILITY CART THEREFOR

David B. Maris, 4601 N. 68th St., #142,
Scottsdale, Ariz. 85251

Filed Sept. 6, 1968, Ser. No. 13,427

Term of patent 7 years

Int. Cl. D12—99; D7—06
U.S. Cl. D49—32

The single feature of the drawing represents a perspective view of a combination twin refuse receptacle unit and utility cart therefor showing my new design.

The opposite sides are mirror images of the sides shown.

I claim:

The ornamental design for a combination twin refuse receptacle unit and utility cart therefor, substantially as shown.
